M. H. SLATER.
TAPE MEASURE HOLDER AND PINCUSHION.
APPLICATION FILED SEPT. 22, 1916.

1,264,341.

Patented Apr. 30, 1918.

UNITED STATES PATENT OFFICE.

MABEL H. SLATER, OF WEBSTER, MASSACHUSETTS.

TAPE-MEASURE HOLDER AND PINCUSHION.

1,264,341.

Specification of Letters Patent. Patented Apr. 30, 1918.

Application filed September 22, 1916. Serial No. 121,551.

To all whom it may concern:

Be it known that I, MABEL H. SLATER, a citizen of the United States, residing at Webster, in the county of Worcester and 5 State of Massachusetts, have invented new and useful Improvements in Tape-Measure Holders and Pincushions, of which the following is a specification.

This invention relates to an improved 10 handy box which is adapted to hold a tape measure and constitutes a pin cushion, the same being provided with a container adapted to hold needles, hooks, eyes, buttons, thimbles, et cetera.

15 The principal novelty of the invention consists in the construction whereby a tape measure is contained within a pin cushion, the pin cushion representing a human head and preferably decorated and designed to 20 represent a Chinese face with ears and mouth and with a braid or pigtail attached thereto which forms a convenient means of support for the device, the pigtail being made of strands of thread, which strands 25 may be separated from the same when it is desired to use them.

The device is so constructed that the end 30 of the tape measure constitutes a stop and is colored to represent a tongue which projects from the mouth of the device while the spring by which said tape measure is retained within the head is released (to allow the tap measure to be drawn rapidly into the mouth) by means terminating adjacent 35 to the ears of the device, so that when one ear is pressed the tape measure will be released and the tape will be rapidly drawn into the mouth until the end of the same projects from the mouth, thus presenting 40 the appearance of a face with the tongue protruding.

Sound producing means are embodied within the head so that as the tape measure is drawn out from the mouth or retracted 45 within the same a squeaking noise is produced, the object of this device being not only to provide a useful device but one which is also amusing.

With these ends in view the invention consists in a device of the character set forth in the following specification and particularly in the combination and arrangement 50 of parts set forth in the claims.

Referring to the drawings:

Figure 1 is a front elevation of my im- 55 proved handy box.

Fig. 2 is a sectional elevation of the same taken on line 2—2 of Fig. 1.

Fig. 3 is a sectional elevation taken on line 3—3 of Fig. 2.

Fig. 4 is a detail section of the cam.

Like numerals refer to like parts throughout the several views of the drawings.

In the drawings, 5 is a casing preferably formed of fabric and being provided with 65 ears 6, 7 and an opening 8 constituting a mouth. The device may be suspended by means of a pigtail 9 constituting a handle formed of strands 10 of thread which may be separated or detached from the same 70 when desired. Within the casing 5 is contained a frame 11, preferably formed of sheet metal and fastened to the top of a hollow cylindrical base 12, which base is provided with a container 13 slidably 75 mounted therein and provided with a closure or cap 14.

The frame 11 has a tubular hub 15 projecting inwardly from one side thereof and upon said hub a reel 16 is rotatably mounted. 80 The reel 16 is actuated in one direction by a spiral spring 17, one end of which is attached to the reel 16 and the other end of which is attached to the hub 15. A tape measure 18 has one end thereof attached to 85 the periphery of the reel 16 and said tape measure 18 projects from the reel through a tube 19 and out of the mouth 8. One end of said tube 19 is affixed to the frame 11 and the other end is attached to the casing 5. 90

Said tape measure has attached thereto upon its outer free end a stop 20 which is preferably colored and shaped to represent the tip of a tongue, while the tape measure itself is colored red to represent a tongue. 95

The reel 6 is rotated in one direction by the tape 18 and in the opposite direction by the spring 17 and is locked in position by arms 21 which are fastened to and extend radially from a tube 22. The arms 21 are 100 forced against the face of the reel 16 by a spring 23 and when in that position engage the teeth 24 formed upon one face of said reel.

The tube 22 projects through the hub 15 105 and terminates adjacent to the ear 6, while

another tube 25 fast to the frame 11 projects therefrom into the ear 7. The arms 21 project through slots 26 in the hub 15.

In order to produce a squeaking noise a bellows 27 is provided, the movable arm 28 of said bellows being operated by an arm 29 pivoted at 30 to an upward extension 31 of the base 12. The arm 29 projects through a slot 32 in the frame 11 and contacts with the inner cam edge 33 of a cam plate 34 which is fastened to the reel 16.

A spring 35 tends to close the bellows 27 and holds the arm 29 against the cam plate 34. The movable arm 28 of the bellows has a whistle 36 attached thereto, so that when the bellows closes by the action of the spring 35 the whistle will be operated.

While I prefer to have the casing 5 of fabric it may be formed of other material without departing from the spirit of my invention. Said fabric is held distended by any suitable yielding material 37, such as cotton batting or the like, and thus it will be seen that the head portion outside the reel forms a pin cushion and also forms a protective means which prevents the mechanism of the reel and the sound producing mechanism from becoming injured.

The general operation of the device hereinbefore specifically described is as follows: The device can be held or suspended by means of the pigtail 9. When it is desired to remove any of the contents from the container 13, said container can be slipped downwardly out of the hollow base 12 for that purpose. When it is desired to draw the tape out of the reel, it may be done by taking hold of the stop 20 and pulling the tape out to the desired distance, whereupon it will be locked by the arms 21 engaging the teeth 24.

When it is desired to release the reel so that the tape shall be wound up it is done by pressing inwardly upon the tube 22. A convenient way of performing this operation is to place a finger against the ear 7 and press the ear 6 with the thumb. Thus the tube 22 will be forced inwardly, the spring

23 will be compressed and the arms 21 will move laterally away from and out of engagement with the teeth 24, whereupon the spring 18 will cause the reel 16 to rotate and the tape 18 will be wound up until the stop 20 strikes the portion of the casing 5 which immediately surrounds the mouth 8. 55

I claim:

1. A device of the character described having, in combination, a casing, in the form of a head, a spring-actuated reel rotatably mounted within said casing and a 60 tape connected to said reel and extending outwardly therefrom through an aperture provided in said casing and representing the mouth of said head and a stop representing a tongue fast to the free end of said 65 tape.

2. A device of the character described having, in combination, a casing in the form of a head, a spring-actuated reel rotatably mounted within said casing, a flexible member connected to said reel extending outwardly therefrom through an aperture provided in said casing and representing the mouth of said head, sound producing means inclosed within said casing and mechanism 75 actuated by said reel to operate said sound producing means.

3. A device of the character described having, in combination, a casing in the form of a head, a spring-actuated reel rotatably 80 mounted within said casing, a flexible member connected to said reel and extending outwardly therefrom through an aperture provided in said casing and representing the mouth of said head, a bellows inclosed within 85 said casing, a whistle connected to said bellows, a cam fast to said reel and an arm connected to said bellows and engaging said cam.

In testimony whereof I have hereunto set 90 my hand in presence of two subscribing witnesses.

MABEL H. SLATER.

Witnesses:

JOHN W. BURGESS,
HENRY F. ELDREDGE.
